CLAIM

The ornamental design for a microcontroller enclosure housing, as shown and described.

DESCRIPTION

FIG. 1 is a front, top and right side perspective view of a microcontroller enclosure housing showing our new design;

FIG. 2 is a front elevation view thereof;

FIG. 3 is a right side elevation view thereof;

FIG. 4 is a left side elevational view thereof;

FIG. 5 is a rear elevation view thereof;

FIG. 6 is a top plan view thereof; and,

FIG. 7 is a bottom plan view thereof.

The broken lines showing the of environment is for illustrative purposes only and forms no part of the claim design.
